(57) **CLAIM**

The ornamental design for a vehicle front bumper cover as shown and described.

DESCRIPTION

FIG. 1 is a front elevational view of a vehicle front bumper cover, showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top, front and left side perspective view thereof; and,

FIG. 7 is a bottom, front and left side perspective view thereof.

The ghosted or low contrasted showing of the vehicle front bumper cover is provided for purposes of illustrating portions that form no part of the claimed design.

1 Claim, 7 Drawing Sheets
